UNITED STATES PATENT OFFICE.

GEORGE B. PICKOP, OF NEW BRITAIN, CONNECTICUT, ASSIGNOR TO P. & F. CORBIN, OF NEW BRITAIN, CONNECTICUT, A CORPORATION OF CONNECTICUT.

DOOR-KNOB.

No. 927,427.

Specification of Letters Patent.

Patented July 6, 1909.

Application filed July 15, 1908. Serial No. 443,584.

To all whom it may concern:

Be it known that I, GEORGE B. PICKOP, a citizen of the United States, residing at New Britain, county of Hartford, Connecticut, have invented certain new and useful Improvements in Door-Knobs, of which the following is a full, clear, and exact description.

My invention relates to improvements in door knobs, and is particularly concerned 10 with the means for securing the knobs to the door.

The object of the invention is to provide a construction whereby the knobs may be secured in operative position without the necessity of using any implement or tool, the 15 construction being such that the knobs may be secured entirely by manual operation.

With these and other objects in view, the invention consists in the construction and 20 arrangement of parts which is illustrated in the accompanying drawings, in which—

Figure 1 is a sectional view through the knobs, taken longitudinally of the spindle. Fig. 2 is a detail side view, partly in section, 25 of an outside sleeve employed in my invention. Fig. 3 is an end view of the same. Fig. 4 is a side view, partly in section, of a driver sleeve comprising a part of the invention. Fig. 5 is an end view of the part shown 30 in Fig. 4. Fig. 6 is a side view of a knob involving the invention.

In the embodiment of my invention which is herein selected for illustration, the device 35 consists of the opposite knobs 1 and 2 mounted upon the ends of the knob spindle 3.

4 and 5 each represent a rose, which is attached in the usual manner to the door. The knob 1 and rose 4 are and may be of usual construction, wherein the knob is permanently secured to the spindle by means of a 40 rivet concealed by the shank of the rose.

The opposite knob and means for securing the same to the spindle involving my invention, comprise the rose 5, having a socket 6, 45 within which is seated the driver sleeve 7, between which and the outside sleeve 8, which is slidably mounted within the socket 6 of the rose, is interposed the spring 9, by which the outside sleeve 8 may be extended 50 in the rose 5, for the purpose hereinafter described. For manual repression of the outside sleeve within the rose and against the spring 9, the outer end of said sleeve is provided with what may be termed a manual 55 ring 10, which, as evident from an inspec-

tion of Fig. 1, will be within easy and convenient reach of the operator. While I have here shown and described this manually operable part as a ring, it is obvious that the same may be in the form of a manually operable lug or finger piece, it being understood that my invention contemplates any purely manually operable part by which the outside sleeve may be repressed within the rose in the attachment of the knob without the use of tools of any description. The driver sleeve 7 is provided with an angular bore 7^a, which slidably fits and is adapted for the operation of the knob spindle. The outer surface of the shank of said driver sleeve is 70 also angular in cross section, and takes within a corresponding angular bore 8^a in the inner end of the outside sleeve. It will be noticed from an inspection of Fig. 1, that when the parts are in assembled position, 75 the shank of the driver sleeve projects about half way through the angular bore of said outside sleeve.

The shank of knob 2, which is here designated as the screwless knob, is provided with 80 an angular portion 2^a at its inner end, which corresponds to the angular bore 8^a within the inner end of the outside sleeve 8, the remainder of the knob shank 2^b being cylindrical to seat within the cylindrical bore 8^b 85 at the outer end of the outside sleeve. The shank of the knob is provided with an internally screw-threaded bore 11 to engage the correspondingly screw-threaded end of the knob spindle. 90

In the assembling and operation of the parts above described, the driver sleeve 7 and outside sleeve 8 are first positioned within socket 6 of rose 5, with the spring 9 interposed between them, as shown in Fig. 1. It 95 is to be understood in this connection that the parts supplied to the trade will have the driver sleeve, outside sleeve and spring preferably permanently assembled so that the only operation necessary for the carpenter or user will be the attachment of the knob alone. 100

With the parts assembled as just described, and in order to attach the knob, the outside sleeve is pushed back or retracted by hand within the rose by means of its manual ring 10 until the outer end of the angular bore 8^a of the sleeve is flush with the outer end of the driver sleeve. The 105 knob is then screwed in upon its spindle 110

until there is no end play apparent between the knobs on opposite sides of the door. The outside sleeve is then released and springs back into normal position with the 5 manual ring 10, covering the connection between the knob and the shank of the rose. At the same time, the angular bore at the inner end of the outside sleeve will interlock the angular ends of both the driver sleeve 10 and knob shank, thereby coupling the driver sleeve and knob so that they will then move as one part and rotate the knob to operate the latch or bolt, but it will be seen that there is no direct operative engagement of 15 the knob shank with the driver sleeve.

The manual ring 10 is made of sufficient depth to at all times cover the gap between the end of the rose and the head of the knob, an annular recess 10^a between the ring and 20 outside sleeve permitting the endwise movement of the ring over the shank of the rose.

What I claim is:

1. In a device of the character described, a knob spindle, a sleeve slidably but non-rotatably mounted thereon and having an externally angular shank, a knob adapted to be screwed upon said spindle and also having an externally angular shank, and a slidably coupling member having a bore adapted to 30 surround and engage said angular shanks of the sleeve and knob to hold the knob against rotation on said spindle.

2. In a device of the character described, a knob spindle, a member slidably but non-rotatably mounted thereon, a knob adapted to be screwed down upon said spindle to abut said member, and a coupling member constructed to engage the abutting ends of said first member and knob to prevent rotation of 40 the latter upon said spindle.

3. In a device of the character described, a knob spindle, a sleeve slidably but non-rotatably mounted thereon, a knob having a shouldered shank with an angular end and 45 adapted to be screwed upon said spindle until its inner end abuts said sleeve, and a spring-actuated coupling sleeve slidably mounted upon the first sleeve and adapted to be repressed thereover to permit positioning

of the knob by rotation and to be normally held by its spring over the junction between the first sleeve and the angular end of the knob shank to hold the latter against rotation on the spindle.

4. In a device of the character described, a 55 knob spindle, a socketed rose surrounding said spindle, a member slidably but non-rotatably mounted upon said spindle within the rose, a knob adapted to be screwed upon said spindle with its shank adjacent said 60 member, a spring-actuated coupling member for said first member and knob mounted upon said first member and adapted to be actuated by its spring to couple said first member and knob, said coupling member having 65 a ring extending beyond the rose to cover the junction between said rose and knob when the knob is in operative position.

5. In a device of the character described, a 70 rose, a knob spindle, a member slidably but non-rotatably mounted thereon, a knob having a shank to be screwed upon said spindle to enter said rose so as to abut said member therein, and a coupling slidably but non-rotatable on said member, said coupling being 75 arranged to non-rotatably engage and disengage the inner end of said shank, and means to hold said coupling member at all times in non rotatable engagement with said first member and normally in non-rotatable engagement with said knob shank to prevent rotation of the latter on said spindle.

6. In a device of the character described, a 80 knob spindle, a socketed rose surrounding said spindle, a knob adapted to be screwed upon said spindle, and securing means for said knob slidably mounted within said rose and including a manually operable exposed ring extending beyond said rose for actuation of the securing means to securing and 90 releasing positions and extending forward over the outer end of the rose to cover the junction between the rose and knob at all times after the parts are assembled.

GEORGE B. PICKOP.
